CLAIM

The ornamental design for underwear, as shown and described.

DESCRIPTION

FIG. 1 is a perspective view of underwear showing my new design;

FIG. 2 is a front elevational view thereof.

FIG. 3 is a rear elevational view thereof.

FIG. 4 is a left side elevational view thereof, the right side elevational view being a mirror image of the left side view.

FIG. 5 is a top plan view of the underwear; and,

FIG. 6 is a bottom plan view thereof.
